Frank L. Broeren, Neenah, Wis., assignor to
Marathon Corporation, Rothschild, Wis., a cor-
poration of Wisconsin

Application August 18, 1949, Serial No. 4,605

Term of patent 14 years

(Cl. D4—3)

To all whom it may concern:

Be it known that I, Frank L. Broeren, a citizen of the United States, residing at Neenah, in the county of Winnebago and State of Wisconsin, have invented a new, original, and ornamental Design for a Dispenser for Sheet Material, of which the following is a specification, reference being had to the accompanying drawing, forming a part hereof.

Figure 1 is a front perspective view of a dispenser for sheet material, showing my new design;

Figure 2 is a rear perspective view;

Figure 3 is a side elevational view thereof drawn to a reduced scale.

I claim:

The ornamental design for a dispenser for sheet material, as shown.

FRANK L. BROEREN.
